UNITED STATES PATENT OFFICE

2,513,503

ADJUSTABLE NOZZLE

Edward John Marshall, Cambridge, England, assignor to Pest Control Limited, Harston, England, a British company

Application November 23, 1946, Serial No. 712,001
In Great Britain November 27, 1945

4 Claims. (Cl. 299—114)

1

This invention relates to an improved adjustable nozzle and is particularly concerned with the provision of an improved adjustable nozzle of the type which produces a whirling spray, particularly for the spraying of orchards.

The known type of nozzle is provided at its forward end with an outlet orifice and is closed at its rear end by a closure plate bored to form a plurality of jets spaced from the axis of the nozzle, each jet intersecting at an angle an axial plane through the nozzle.

It has been discovered according to this invention that a spray of more uniform particle size and capable of greater variation in width can be produced by providing the spray nozzle with a plate having a plurality of jets spaced from the axis of the nozzle, and means for varying the angle at which each jet intersects an axial plane through the nozzle.

Accordingly the present invention provides an improved adjustable nozzle of the type which produces a whirling spray, including a plate provided with a plurality of jets spaced from the axis of the nozzle, and means for varying the angle at which each jet intersects an axial plane through the nozzle.

Preferably the adjustable nozzle is internally tapered towards an outlet orifice at its forward end and is provided with a closure plate at its rear end, a plurality of apertures in the closure plate spaced from the axis of the nozzle, jet members associated with the apertures, and means for varying the angle at which each jet member intersects an axial plane through the nozzle, i. e. changes its angular displacement relative to another such jet member.

The jet members may be associated with the apertures in the closure plate by means of ball-and-socket joints.

Preferably the apertures are enlarged rearwardly to form conical or part-spherical seatings which receive the rounded forward ends of longitudinally bored jet members, the rounded rear ends of which are received in similar seatings in a co-axial supporting plate spaced from the closure plate. Provision is made for relative rotation of the two plates and for the relative axial motion between the two plates necessary to follow up the foreshortening of the jet members as their inclination varies.

The two plates may be co-axially mounted in the cylindrical barrel of a co-axial body piece receiving the rear end of the nozzle. The nozzle and closure plate may be permitted limited rotation but restrained from axial movement,

2

whilst the supporting plate is restrained from rotation but is constrained by resilient means to move axially so as to follow up the foreshortening of the jet members on rotation of the nozzle and closure plate.

A preferred embodiment of the invention will now be described and illustrated with reference to the accompanying drawings, in which:

Fig. 1 is an elevation partly in section of an improved spray nozzle,

Fig. 2 is a plan view on an enlarged scale of the rear face of the closure plate,

Fig. 3 is a section on the line III—III thereof,

Fig. 4 is a plan view on an enlarged scale of the front face of the supporting plate,

Fig. 5 is a section on the line V—V thereof, and

Fig. 6 is an enlarged detail showing a jet member.

Referring now to Fig. 1 of the drawings, a cylindrical body piece 2 internally flanged at its forward end receives a conical nozzle 4 externally flanged at its rear end and seating against a washer 3 retained by the internal flange of the body piece. An adjusting ring 4, secured to the nozzle 4 by a set screw 5, is mounted for rotation on the forward end of the body piece 2. The ring 4 has a depending skirt cut away through 90°, and the cut away portion 6 co-operates with a stop 7 projecting from the body piece 2 to limit the rotation of the ring 4. A closure plate 8 is secured to the flanged base of the nozzle 4 by screws 9 passing through holes 10 (see Figs. 2 and 3). The plate 8 is provided with coned seatings 11 receiving the hemispherical forward ends of longitudinally bored jet members 12 (Fig. 6). A flanged supporting plate 13 slidably mounted in the body piece 2 is restrained from rotation by the reduced plain end of a screw 14

engaging in a slot 14a (Figs. 4 and 5), and receives the hemispherical rear ends of the jet members 12 in coned seatings 15. A compression spring 16 bears on the rear face of the supporting plate 13 and is retained by a ring 17 screwed into the rear end of the body piece 2. A coupling 18 provided with a washer 19 may be used for attaching the nozzle body to a spray lance or hose.

Preferably the seatings 11 in the closure plate 8 and the seatings 15 in the supporting plate 13 lie on pitch circles which are sections of a cone having its apex at the centre of the outlet orifice, so that when the jet members 12 each lie in an axial plane through the nozzle, a straight line can be drawn from the outlet orifice of the nozzle

le through the bores of the jet members. The nozzle is shown in this position in Fig. 1, with the stop 7 abutting one end of the cut-away portion 6 of the ring 4. As the ring 4 is rotated, the nozzle 1 turns on its seating washer 3 carrying with it the closure plate 8. The jet members 12 are progressively inclined and the spring-urged supporting plate 13 follows up the foreshortening of the jet members 12. A limit is set to the rotation of the ring 4 by the stop 7 abutting the other end of the cut-away portion 6.

I claim:

1. An adjustable whirling spray nozzle comprising an internally forwardly tapered nozzle piece, an outlet orifice at the forward end of said nozzle piece, a closure plate at the rear end of said nozzle piece, a plurality of rearwardly enlarged apertures in said closure plate spaced from the axis of said nozzle, a supporting plate spaced axially from said closure plate, a like number of forwardly enlarged apertures in said supporting plate spaced from the axis of said nozzle, a like number of jet members associated with the two said plates, the said jet members having rounded forward ends seating in said apertures in said closure plate and rounded rear ends seating in said apertures in said supporting plate, said closure plate being mounted for rotation relative to said supporting plate about the axis of said nozzle to vary the inclination of said jet members, and said closure plate and said supporting plate being mounted for axial movement relative to one another to vary the distance between the two said plates as the inclination of the said jet members varies.

2. An adjustable whirling spray nozzle comprising an internally forwardly tapered nozzle piece, a co-axial cylindrical body piece receiving the rear end of said nozzle piece, an outlet orifice at the forward end of said nozzle piece, a co-axial circular closure plate carried on the rear end of said nozzle piece, a plurality of rearwardly enlarged apertures in said closure plate spaced from the axis thereof, a co-axial circular supporting plate mounted rearwardly of said closure plate in said cylindrical body piece, a like number of forwardly enlarged apertures in said supporting plate spaced from the axis thereof, a like number of jet members associated with the two said plates, the said jet members having rounded forward ends seating in said apertures in said closure plate and rounded rear ends seating in said apertures in said supporting plate, said closure plate being mounted for rotation relative to said supporting plate about the axis of said nozzle to vary the inclination of said jet members, and said closure plate and said supporting plate being mounted for axial movement relative to one another to vary the distance between the two said plates as the inclination of the said jet members varies.

3. An adjustable whirling spray nozzle com-

prising an internally forwardly tapered nozzle piece, a co-axial cylindrical body piece receiving the rear end of said nozzle piece, an outlet orifice at the forward end of said nozzle piece, a co-axial circular closure plate carried on the rear end of said nozzle piece, said closure plate and said nozzle being mounted for limited rotational movement only in said body piece, a plurality of rearwardly enlarged apertures in said closure plate spaced from the axis thereof, a co-axial circular supporting plate mounted rearwardly of said closure plate in said cylindrical body piece, said supporting plate being mounted for axial movement only in said body piece, a like number of forwardly enlarged apertures in said supporting plate spaced from the axis thereof, a like number of jet members associated with the two said plates, the said jet members having rounded forward ends seating in said apertures in said closure plate and rounded rear ends seating in said apertures in said supporting plate, and resilient means urging said supporting plate axially forward towards said closure plate.

4. An adjustable whirling spray nozzle comprising an internally forwardly tapered nozzle piece, a co-axial cylindrical body piece receiving the rear end of said nozzle piece, an outlet orifice at the forward end of said nozzle piece, a co-axial circular closure plate carried on the rear end of said nozzle piece, a plurality of rearwardly enlarged apertures in said closure plate arranged on a pitch circle, a co-axial circular supporting plate mounted rearwardly of said closure plate in said cylindrical body piece, a like number of forwardly enlarged apertures in said supporting plate arranged on a second pitch circle, the two said pitch circles forming sections of a cone having its apex at the centre of the outlet orifice, a like number of jet members associated with the two said plates, the said jet members having rounded forward ends seating in said apertures in said closure plate and rounded rear ends seating in said apertures in said supporting plate, said closure plate being mounted for rotation relative to said supporting plate about the axis of said nozzle to vary the inclination of said jet members, and said closure plate and said supporting plate being mounted for axial movement relative to one another to vary the distance between the two said plates as the inclination of the said jet members varies.
